UNITED STATES PATENT OFFICE.

CHARLES E. SMITH, OF BRIDGEPORT, CONNECTICUT.

TRY-SQUARE.

SPECIFICATION forming part of Letters Patent No. 760,031, dated May 17, 1904.

Application filed March 22, 1904. Serial No. 199,384. (No model.)

To all whom it may concern:

Be it known that I, CHARLES E. SMITH, a citizen of the United States, residing at Bridgeport, in the county of Fairfield and State of Connecticut, have invented certain new and useful Improvements in Try-Squares; and I do hereby declare the following to be a full, clear, and exact description of the invention, such as will enable others skilled in the art to which it appertains to make and use the same.

My invention relates to certain new and useful improvements in try-squares, and has for its object to produce a very simple and effective device of this description; and with these ends in view my invention consists in certain details of construction and combination of parts, such as will be hereinafter fully set forth, and then specifically designated by the claim.

In the accompanying drawings, Figures 1 and 2 are plan views of opposite faces of my improved square; and Figs. 3 and 4 are sections taken, respectively, at the lines *x x* and *y y* of Fig. 1.

Similar letters of reference denote like parts in the several figures of the drawings.

Heretofore devices of this description have been constructed by securing a thickening-piece to one face of the handle portion of the square; but both side edges of said piece have been coincident with the side edges of the handle portion of the square, so that no benefits could be obtained from any graduation along the outer side edge of said handle, and, moreover, the thickening-piece itself has been made perfectly plain, with no graduations appearing upon the same.

My improvement aims to provide the usual form of try-square with a thickening-piece applied to its handle, so that the device may be used after the manner of the ordinary T-square, while at the same time the efficiency of the main portion of the try-square is not lessened in the slightest degree.

a is the blade, and *b* the handle portion of an ordinary try-square, preferably made in one piece from sheet metal.

c is the thickening-piece, which is prefer-

ably made from sheet metal, with the extremities bent at right angles and terminating in rivets *d*. This piece *c* is secured to the handle portion *b* by assembling these rivets within perforations *e* in the blade, the extreme ends of said rivets being then headed in the usual manner. The inner edge of the piece *c* is flush or coincident with the inner edge of the handle portion *b*, but the width of the piece *c* is considerably less than the width of this handle portion, so that the outer edge of the handle portion *b* projects beyond the outer edge of the piece *c*, and the length of this piece *c* is less than the length of the handle portion, so that there is quite a clearance between the inner end of the piece *c* and the outer edge of the blade *a* near the point where said blade and handle portions join. I prefer also to make this piece *c* of such length that there is a clearance between the outer end of said piece and the outer end of the handle portion.

The blade and the handle are graduated on one face along the outer and inner edges, while on the other face these graduations appear except along the inner edge of the handle portion; but both the inner and outer edges of the piece *c* are graduated, so that the efficiency of the try-square is not lessened.

Owing to the fact that the outer edge of the handle portion projects beyond the outer edge of the piece *c*, the efficiency of the try-square is increased, since this leaves the entire outer edge of the handle portion free to be inserted within confined angles, and in this connection I would also state that the clearance between the outer edge of the blade and the inner end of the piece *c* renders my improvement of great practical utility, particularly in view of the fact that the outer edge of this piece *c* is graduated.

I do not wish to be understood as claiming, broadly, any construction whereby there is a clearance left between the inner end of the piece *c* and the outer edge of the blade *b*, nor do I wish to be understood as claiming, broadly, the thickening of one face of the handle portion of a try-square by means of a sheet-metal or other strip applied thereto; but

What I do claim as new, and desire to secure by Letters Patent, is—

A try-square composed of an L-shaped main portion and constituting a handle and a blade, 5 and a separate piece secured to one face of said handle and extending at its inner end only part way of the length of said handle and to a point a short distance from the outer edge of said blade, the inner edge of said piece be-

ing coincident with the inner edge of said handle while the outer edge of the latter projects beyond the outer edge of said piece.

In testimony whereof I affix my signature in presence of two witnesses.

CHARLES E. SMITH.
